UNITED STATES PATENT OFFICE.

FREDERICK L. H. SIMS, OF SOUTHAMPTON, ONTARIO, CANADA.

FOLDING COUCH AND THE LIKE.

Application filed July 24, 1922. Serial No. 577,261.

To all whom it may concern:

Be it known that I, FREDERICK L. H. SIMS, of Southampton, in the county of Bruce, Province of Ontario, Canada, a subject of the King of Great Britain, have invented certain new and useful Improvements in Folding Couches and the like, of which the following is a specification.

This invention relates to a couch particularly adapted to serve as a housing for a folding bed, and my object is to devise a couch of this type in which, though the folding bed for which it forms a housing fits close up to the under side of the couch seat, the latter may be given an adequate depth of spring and yet have its upper surface no higher than is usual or desirable; to provide convenient means to get the seat and arms out of the way when the device is used as a housing for a folding bed and especially when it is desired to use the bed in a position partly between the sides of the housing; and to so arrange the arms that they may be supported in the usual upright position, set down to form lateral extensions of the seat or held in an intermediate inclined position.

I attain my object by means of the constructions hereinafter described and illustrated in the accompanying drawings in which—

Fig. 1 is a front view of the bed housing constructed in accordance with my invention, parts being broken away to expose the construction;

Fig. 2 a plan view of the same partly broken away;

Fig. 3 a vertical cross section on the line 3—3 in Fig. 2 looking towards the left hand side;

Fig. 4 a horizontal sectional detail of the interlocking parts of the fall board and main frame;

Fig. 5 a vertical sectional detail of the said lock;

Fig. 6 a horizontal sectional detail illustrating the method of locking the movable couch arms to the back; and

Fig. 7 a detail illustrating, in front elevation, different positions of one of the sofa arms.

In the drawings like numerals of reference indicate corresponding parts in the different figures.

The frame of the housing comprises suitably formed ends 1 and a back 2 rigidly con-

nected with the ends by means of the brackets 24, and suitably shaped to support the spring padding and upholstery 3 as indicated in outline in Fig. 3. The seat is formed as a separate removable part and 4 is the frame thereof, which may be covered and provided with springs in the ordinary manner, and which is adapted to support the movable spring cushions 5 as is common in the art and also the front board 10 as hereinafter described.

The back part of the seat is supported on the metal brackets 6, which are secured to and extend forwardly from the frame of the back. These brackets are narrow in proportion to their depth, and therefore enable the movable sofa arms, hereinafter referred to, to lie up close to the ends of the seat frame. At each end the seat frame is provided with a projection 7 adapted to slide on the adjacent bracket 6. The rear end of each bracket is formed with a slight depression 9, in which the projection 7 normally lies. Thus when the seat is drawn forward it rises slightly, the purpose of which rise will hereinafter appear. The upper surface of the bracket on which the projection slides, it will be noted, is inclined upwardly and forwardly so that the seat continues to lift slightly as pulled forward, and thus, when it is finally swung to a substantially upright position, its then underside is well clear of the upper surface of the mattress or bedding of the folding bed which may be contained within the housing.

A shoulder 8 is formed on the forward end of each bracket, and serves to limit the extent to which the seat frame can be pulled forwards.

The forward side of the seat frame is supported in the following manner. A front board 10 is hinged to the forward side of the seat frame. At each side of this front board I form or secure vertical ribs 11, through which passes a horizontal pin 12. The adjacent end 1 of the main frame is formed with an upwardly and outwardly facing hook 13 on each end into which the adjacent pin 12 may drop, as indicated particularly in Fig. 5 of the drawing. When the pins 12 are so engaged, the front board is held closely in position against the ends 1, and is held from lateral movement relative thereto by the engagement of its vertical ribs 11 at the opposite sides of the front part of the end. As the front board is

hinged to the seat, the latter and the movable arms carried thereby, as hereinafter described, are securely held from all horizontal movement by the construction just described. When the seat and front board are to be lifted up out of the way, the front board is lifted sufficiently to disengage the pins 12, the seat can then be drawn forward till the projections 7 contact with the shoulder 8. The projections and shoulders then form temporary journals and bearings and the seat may be turned up to the position shown in dotted lines in Fig. 3, the front board falling naturally to a position in which it hangs close against the formerly underside of the seat.

The movable arms 14 are supported in the following manner. These arms are formed on a suitable wooden framework, and are upholstered in a suitable manner, the outline only being shown in the drawings. Each sofa arm is formed with adjacent sides 15 and 16 substantially at right angles to one another. It will be noted that the thickness of the arm is such that when it lies with the side 15 resting horizontally on top of the adjacent end 1, the opposite side is substantially level with the upper surfaces of the cushions 5 of the seat. The position of the ends of the seat relative to the ends 1 of the frame is always such that when the arm is resting thereon with the side 16 in contact therewith, the side 15 of the arm is approximately flush with the outer side of the end and the opposite side of the arm close up to the end of the adjacent cushion 5 of the seat. The result is that when the arms are vertical the device presents as attractive an appearance as any ordinary sofa, while, when one or both arms are turned down, they form in effect extensions of the seat.

To enable the arms to be held in either position described, and also to enable them to be held, when desired, in the intermediate diagonal position shown in dotted lines in Figs. 1 and 7, I provide special hinges or links arranged in the manner I will now describe. A hinge member 17, preferably of considerable length as is seen particularly in Fig. 2, is provided with a hinge pin 18, which is journalled in eyes 19 secured to the side of the seat frame close to its lower edge. The other side of the hinge member 18 is provided with a hinge pin 20, which is pivoted in bearing members 21 secured to the side 16 of the adjacent movable arm, the bearing being located approximately near the middle of the side. The positions of the eyes 19 and the bearings 21 is planned to enable the sofa arm to occupy the positions hereinbefore described and illustrated. The hinge member 17 being formed of thin sheet metal occupies very little room, and its presence is in no

wise noticeable whether the sofa arm be horizontal or vertical. Sometimes it is convenient to have the arm occupy an intermediate inclined position, as shown in Figs. 1 and 7. The hinge member 17 will take most of the strain when the arm is in this position, provided the arm is locked in some way. For this purpose I secure to the rear of each arm a plate 22 having holes formed therein. When the arm is in the inclined position shown the hole 24 is brought into alignment with the sliding bolt 25 carried by the back in its inclined position. When the arm is in the upright position the hole 23 is in alignment with the bolt, and, by sliding forward the bolt, the arm may be locked in its upright position. As the housing is always spaced somewhat from the wall due to the projection of the skirting board there is always sufficient room for the operation of this bolt. This bolt is not seen except when in the withdrawn position.

This housing is particularly adapted to contain the folding bed action which is shown and described in my co-pending application No. 577,262 filed July 24th, 1922. An important requirement of a housing for this purpose is that there should be as much height as possible provided in the housing for the frame of the folding-bed action, while, when the device is used as a sofa, it is equally as important that there shall be ample depth of seat to provide for the usual spring foundation in the seat, and for special spring cushions on top of the seat, without exceeding the usual height of the top of the finished seat from the floor.

From an inspection of Fig. 1, it will be seen that the seat is considerably shorter than the width of the fixed frame and the bottom of the seat frame may therefore be dropped below the level of the tops of the ends, thus giving the seat ample depth without interference with the mattress foundation of the action, while sufficient extra height is provided within the housing adjacent the ends to provide the extra height demanded to receive the sides of the frame of the action which, in the folded action, extend above the level of said mattress foundation.

The gaps between the sides of the seat frame and the ends 1 are at all times closed by the arms in whatever position they may be.

It is evident that in addition to serving as a suitable housing for a folding bed, the device itself may be used as a sofa or as a couch or as a divan with both arms in a horizontal position, the arms being positioned according to the requirements of the user.

It will be noted that, when the seat is drawn forward as a preliminary to turning it to the upright position, the projections

7 lift up out of the depressions, and the arms 14 which have previously been turned down to the horizontal position are at once lifted clear of the frame ends 1 so that the 5 upholstery on the sides 15 is not injured by rubbing on the upper sides of the ends.

What I claim as my invention is:—

The combination of a sofa having a fixed 10 end member and a seat; a movable sofa arm adapted to lie with one side either abutting the end of the seat or resting on the fixed

end member; a hinge pivotally connected with the sofa adjacent the seat and pivotally connected with the said side of the movable arm midway between its inner and outer 15 edges, whereby said edges travel in planes substantially at right angles to one another as the said end is swung on the hinge.

Signed at Southampton, Ontario, this 12th day of July, 1922.

FREDERICK L. H. SIMS.
